Primary Examiner — Cynthia Underwood(74) *Attorney, Agent, or Firm* — Roylance, Abrams, Berdo & Goodman, L.L.P.(57) **CLAIM**

The ornamental design for a clip-on bonding washer, as shown and described.

DESCRIPTION

FIG. 1 is a perspective view of a clip-on bonding washer according to a first embodiment of the invention, taken from the top, front and right side thereof;

FIG. 2 is a perspective view of the washer of FIG. 1 taken from the top, front and left side thereof;

FIG. 3 is a perspective view of the washer of FIG. 1 taken from the bottom, front and right side thereof;

FIG. 4 is a perspective view of the washer of FIG. 1 taken from the bottom, front and left side thereof;

FIG. 5 is a top plan view of the washer of FIG. 1;

FIG. 6 is a bottom plan view of the washer of FIG. 1;

FIG. 7 is a right side elevational view of the washer of FIG. 1, the opposite side being the mirror image of that shown;

FIG. 8 is a front elevational view of the washer of FIG. 1; and,

FIG. 9 is a rear elevational view of the washer of FIG. 1.
